UNITED STATES PATENT OFFICE.

EDWARD P. NOYES, OF WINCHESTER, MASSACHUSETTS, ASSIGNOR, BY MESNE ASSIGNMENTS, TO CHARLES W. BROWN, TRUSTEE, OF PITTSBURGH, PENNSYLVANIA.

LIQUID-FEEDER FOR BURNERS, &c.

1,141,258.

Specification of Letters Patent.

Patented June 1, 1915.

Application filed August 16, 1906, Serial No. 881,114. Renewed October 2, 1914. Serial No. 864,840.

To all whom it may concern:

Be it known that I, EDWARD P. NOYES, a citizen of the United States, residing at Winchester, in the county of Middlesex and State of Massachusetts, have invented certain new and useful Improvements in Liquid-Feeders for Burners, &c., of which the following is a specification.

This invention relates broadly to liquid and gas mixers and is especially designed to furnish a means whereby air and liquid fuel may be combined in combustible proportions for internal combustion burners whether of the continuous burning or intermittent or explosive type.

My invention relates more particularly to carburetors or mixers of the so-called "open-jet" type in which the liquid is entrained in the air or other gaseous current partly by aspiration or ejector action and partly by differences of gaseous pressure exerted at opposite ends of the fuel column. Assuming the device to be a liquid-fuel carburetor, the differences of pressure therein are caused by a resistance located in the path of the air stream or current at a point or points anterior to the mixing chamber, and the air pressure anterior to said resistance is established on the surface of the fuel in a reservoir communicating with the fuel inlet of the mixing chamber.

One object of my invention is to provide a substantial but stable and delicately controllable difference of air-pressure between the reservoir and the mixing chamber regardless of the volume of air passing at the moment, for the purpose of insuring an adequate flow of fuel under all conditions.

Another object is to maintain this pressure-difference substantially constant, and a third object is to control and limit the fuel aspirating action by means of such constant pressure-difference. As a secondary expedient I may provide for the introduction of gaseous fuel along with the liquid fuel and air under a control similar to that imposed upon the air flow.

The accompanying drawing represents a diagrammatic view, partly in section, showing an apparatus constructed according to my invention.

1 indicates a mixing chamber for the air and atomized liquid fuel, 2 is an air-pipe or conduit leading into said chamber in fuel-entering relation to the nozzles hereinafter

described, and 3 is an eduction pipe leading from said chamber to the engine or other user. The pipes 2 and 3 and the interposed mixing chamber constitute in effect one conduit or passage, and said mixing chamber may be that of an ordinary carburetor, or it may pertain to a constant-pressure internal-combustion burner of which there are several types well-known to those skilled in the gas-engine art. Pipe 2 may either be a compressed-air pipe or may have its air flow induced by suction from an atmospheric or sub-atmospheric source. In either case the pipe 8 hereinafter described receives substantially the pressure of the mixing chamber 1, or some fractionally lower pressure, due to resistance in that part of the passage posterior to the mixing chamber and bearing a substantially constant relation to the pressure in 1.

In the air-pipe 2 is placed a resistance-valve 4 whose stem is attached to a septum or diaphragm 5 having chambers 6 and 7 above and below it. The chamber 6 is open to the air-pressure on the initial or anterior side of valve 4, received through the anterior section 2a of the air pipe, and the chamber 7 receives the pressure posterior or terminal to said valve (and preferably also posterior to the aspirating elements of the mixing chamber as shown) through pipe 8. A spring 9 attached to the valve-stem and to a lever 10 pivoted at 11, exerts a substantially constant valve-closing pressure in aid of the pressure in chamber 7. The upper end of this spring may either be held in a fixed position by a set-screw 12 which locks the lever 10, or the pressure of the spring may be replaced by that of a changeable weight 13 suspended from the outer end of the lever. Set-screw 12, which is mounted on a suitable fixed support, when tightened locks the lever 10, and when loosened allows said lever to turn freely on its pivot 11, the spring in the latter case being practically eliminated except as an elastic connection. In either case the mechanical pressure acting in aid of the posterior fluid pressure is normally constant, although subject to adjustment by changing the weight (set-screw 12 being loosened) or fixing the lever 10 in the set-screw so as to alter the tension of different angular positions by means of spring 9.

14 is a reservoir for liquid fuel, having an air

outlet through a pipe 15 and a continuation 16 thereof, past a needle-valve 17 and a jet-nozzle or fuel inlet 18 into the mixing-chamber 1.

27 is a second nozzle, surrounded by the air inlet or opening 2^a to the mixing-chamber 1, and it will be noted that these inlets have substantially the usual ejector relation causing the air to aspirate the fuel. The presence of nozzle 27 is not essential, but it may be used as an entrance for a supply of fuel gas or air as hereinafter described. The reservoir 14 may be filled through the pipe 15 by way of a pressure-retaining lock 20 having lock-valves 21, 22 at opposite ends and surmounted by a filling funnel 23 whereby the liquid-level may be maintained substantially constant by manual attendance, or it might be otherwise filled as desired, and any known or suitable means for automatically maintaining a constant fuel-level may of course be adopted.

24 is a pipe leading from the anterior section 2^a of air-pipe 2 to the upper part of reservoir 14 in order to carry to the surface of the fuel therein the air-pressure anterior to the valve 4. Where the anterior pressure is atmospheric, the pipe 24 would not be essential, as in that case reservoir 14 may be directly open to the atmosphere, and the pipe section 2^a could also practically be dispensed with, but this pipe or some equivalent is highly important when the pressure anterior to valve 4 is either above or below the atmospheric.

In the operation of this apparatus the valve 4 with its associated parts automatically maintains a substantially fixed difference between the pressure in the mixing chamber 1 and the pressure in the initial section of pipe 2, this difference being measured by the tension of spring 9 (or, if desired, by weight 13). The pressure of the spring remains substantially constant for extensions and contractions thereof (representing the travel of valve 4) which are small in comparison with its length and stiffness. If there were no flow of air, the spring would close valve 4 by an upward movement past its port in the valve casing, and in order to open this valve the anterior pressure must be in excess of the posterior pressure by an amount sufficient to overcome the tension of the spring. Given this excess, which may occur either by reason of a rise of the anterior, or a fall of the posterior pressure, the valve opens and an air-flow ensues. If this flow is sufficient to raise the posterior pressure so as to establish a smaller pressure-difference than the standard for which spring 9 is set, the valve partially closes until the normal pressure-difference has been restored, and so on. Hence during any flow of air within the limits of controlling capacity of the apparatus, the drop in pressure imposed by

the valve upon the air-current is substantially constant, and is also independent of the amount of air pressure or the volume of air flow, the valve opening to an amount which will accommodate the volume of air seeking passage at any moment. This differential constant-reduction controller or regulator is not here claimed *per se*, being made the subject of a separate Patent, No. 889,185, in which, as also in my Patent No. 868,358, are described a constant-flame generator occupying substantially the position of the element 1 which is herein termed a "mixing-chamber." The interior construction of this element is immaterial to the present invention since my invention applies equally to a constant-pressure generator or to a suction carbureter in which the mixing-chamber, as is well known, is practically a part of the induction-pipe leading to the motor. The employment of the regulator above-described, using a differential septum larger than the valve, and especially when the valve 4 is pressure-balanced in the manner shown or otherwise, affords a desirable sensitiveness in the apportionment of air-flow to liquid-fuel flow by the mode which I have described, and tends to minimize evil inertia-effects caused by pulsations in the air-flow, but it is to be understood that I do not wholly confine myself to the employment of a septum distinct from the valve itself. In practice the valve will of course be subject to a slight leakage in order to move freely, and this leakage or other uncontrollable air may serve to equalize the anterior and posterior pressures when the engine stops, so as to prevent flooding and also to provide sufficient air to mix with the fuel for starting purposes before the valve responds to a relative fall of pressure in the mixing-chamber, but the passage of this relatively small uncontrolled stream of air need not materially affect the command of total pressure-drop exerted by the valve and septum.

Since the diaphragm 5 and its attached valve member command substantially the entire air-supply to the mixing-chamber 1, the difference of pressure created thereby is felt at opposite ends of the fuel-column, in reservoir 14 and at nozzle 18 respectively, and hence there is always an adequate supply of fuel ready to meet the air in the mixing chamber, even at the lowest air velocities. This pressure-difference serves to lift the fuel from the reservoir to the nozzle if the latter is above the former as shown, and in that case the effective fuel-feeding force is the pressure-difference minus the fuel head.

I consider it an advantage to maintain a fuel-feeding pressure-difference having a controllable and adjustable relation to the mixing-chamber pressure, which relation may

be that of substantial constancy at any adjustment; because then the amount of the fuel-feeding pressure-difference can be more readily determined and adjusted to meet all the varying conditions of air-flow or of intake pressure (*i. e.*, at, above, or below the atmospheric) and also because it enables any variable fuel-feeding influence to be treated substantially as a separate factor. Such a variable in the present case is the aspirating or fuel-ejecting action due to the velocity of the air current past the fuel-nozzle,—which velocity varies with the volume of the air-flow. By the means above described I am enabled to produce a flow of fuel substantially proportionate to said air-flow, so that, at any given pressure-level, the weights or quantities will remain in a substantially constant ratio, notwithstanding the changes occurring in said quantities, to meet the varying demands.

Heretofore in the common type of carbureters, and especially in those employing a primary air-inlet of constant aperture and a secondary air-inlet controlled by an automatic loaded valve, the air-pressure in the mixing chamber has not borne any definite relation to the pressure acting on the fuel in the reservoir or float chamber, and the former would fall away indefinitely with increasing volumes of air-flow, particularly at times before the automatic valve comes into action. In such carbureters the feeding of fuel by pressure-difference and the so-called aspirator feeding influence are so intermingled that it is difficult to ascribe separate values to, or exercise intelligent control upon either of them; while at low air-velocities the feeding of fuel is generally deficient. By means of my invention the first named of these forces may be separated by making it substantially constant and subject to predetermined variation by simple mechanical adjustments, and the latter force is or may be delicately controlled by embracing, within the substantially constant total pressure-drop, that local and varying pressure-drop occurring as between the pressures in those portions of the air-flow conduit which are immediately anterior, and those which are immediately posterior to the aspirator, and which in particular determine the aspiration effects. In the particular illustration of this case, this is accomplished by taking the pressure for chamber 7 from a point posterior to the aspirating elements 18, 27. Under these conditions, and strictly speaking, it is obvious that the local pressure at the outlet of fuel-nozzle 18 is not the same as the local pressure in the ordinary automatic-dilution carbureter having an open primary air-passage, a secondary air-passage, a varying terminal pressure, and a velocity of air-flow past the fuel-jet corresponding to all

these conditions; but if that pressure created in the throat of an ejector whose immediately anterior pressure is a variable, intermediate between the pressure anterior to a valve such as 4 and the pressure in the mixing chamber, the latter permissibly bearing a fixed relation to the primary or intake pressure as stated, so that this local pressure-drop will then be a varying percentage of a substantially constant pressure-difference. This action is made possible by the fact that the pressure controlling the automatic valve or septum on its posterior side is not merely the pressure posterior to the valve itself but is the pressure posterior to the aspirator. The simple and novel expedients of universal character, thus made applicable, afford to the person skilled in the art the power of apportioning air and fuel with precision over a wide range. One result among others is the automatic limitation imposed upon that increase of fuel-supply, which ordinarily is the consequence simply of increased ejector-action as the demand upon the motor increases, and which tends to an oversupply of fuel, but imperfectly compensated for by the action of the ordinary automatic air valve.

Various changes of embodiment may be made without departing from my invention.

In addition to the air-pipe 2 I have shown a fuel-gas pipe 25 leading to the mixing-chamber 1 by way of nozzle 27 and containing a valve 26 in the automatic controller on the same stem as valve 4 and hence subject to the same controlling influences. This pipe may be used to supply to the mixing-chamber combustible gas, preferably under the same initial pressure as the air, and if so, subject as just indicated to the same pressure drop, and the gas and liquid fuel may both be burned together if desired, or the oil may be burned alone. In some cases I have sent air through both the pipes 2 and 25 in order to secure the most efficient mixing and vaporizing action at the nozzles. The two avenues of air supply are not however essential, and if a gaseous-fuel supply is not required the elements 25, 26 and 27 may be omitted.

I claim,—

1. In a liquid-fuel carbureter, the combination of a passage including a mixing-chamber having air and fuel inlets constituting an aspirator with a restricted air throat, an automatic air valve commanding substantially the entire air ingredient of the mixture and biased to close, said valve being differentially controlled by the air-pressure anterior to itself tending to open the valve and the mixing-chamber pressure posterior to said aspirator tending to close the valve, and a fuel reservoir connected with said fuel inlet and subject in its upper portion to sub-

stantially the air pressure anterior to said valve.

2. In an air and liquid-fuel mixer, the combination of a mixing chamber having an inlet for substantially its entire air supply and a pressure-balanced valve controlling said inlet, an aspirator provided with a restricted air throat in the course of said air supply, a liquid-fuel reservoir subject to the air-pressure anterior to said valve, and having a fuel discharge duct provided with an outlet to said chamber at the aspirator, above the level of the reservoir, and a septum attached to the air-inlet valve and subject in one direction to the mixing-chamber pressure and to a substantially constant valve-closing force, and in the other direction to the air-pressure anterior to the valve.

3. In an air and liquid-fuel mixer, the combination of a mixing chamber having an air-supply pipe and an ejection pipe, an inlet valve in said air-supply pipe controlled differentially by the air-pressure anterior and posterior to itself, a fuel-reservoir having a discharge outlet to the mixing chamber, and a duct connecting the upper space of said fuel reservoir with a point in the air-supply pipe anterior to the inlet valve.

4. In combination, a mixing chamber having inlets for air, gaseous fuel and liquid fuel, the liquid-fuel inlet being of normally-fixed aperture, air and gas valves controlling the air and gaseous-fuel inlets and both controlled automatically by the pressures anterior and posterior to the air valve, and means for maintaining a pool of liquid fuel with its surface subject to the anterior air pressure for supplying the liquid-fuel inlet.

5. In combination, a mixing chamber having liquid-fuel and gaseous-fuel inlet nozzles and an inlet for air-supply, valves controlling respectively the air and gaseous-fuel inlets, controlled differentially by the air-pressure anterior and posterior to the air valve, and means to feed liquid fuel to the liquid-fuel nozzle by the difference of pressure imposed by the air valve.

6. In a liquid-fuel carburetor, the combination of a passage including a mixing chamber having air and fuel inlets constituting an aspirator having a restricted air throat, and an air-supply conduit connected with said air inlet, a valve in said conduit dominating the relation between the air pressure anterior to itself and that in the mixing chamber, a septum connected with said valve and subject on one side to said anterior pressure and on the opposite side to the pressure in said passage posterior to the aspirator, and a fuel reservoir connected

with said fuel inlet and subject in its upper portion to said anterior pressure.

7. In combination in a liquid-fuel-and-air mixer, an anterior pressure of air-supply, a mixing-chamber, main and minor air-passages from air-supply to mixing-chamber, a throttle on the main air-passage arranged to maintain a substantially constant deficit of air-pressure in the mixing-chamber, a fuel-reservoir below the level of the mixing-chamber and connected thereto by a fuel-supply passage terminating in an aspirator operated by the minor air-supply, and means controlled by the major air-throttle for varying the volume of liquid aspirated into the mixing-chamber.

8. In combination in a liquid-fuel and air mixer, an anterior air-supply, major and minor mixing-chambers, a fuel-reservoir having its liquid-surface below the level of said mixing-chambers, major and minor air-ducks arranged to aspirate liquid-fuel or its vapor from said reservoir to the respective mixing-chambers, and a throttle controlling the air-flow through the two ducts unequally.

9. In combination in a liquid-fuel-and-air mixer, an anterior air-supply, a major mixing-chamber, a minor mixing-chamber, a fuel-reservoir having its liquid-level below both mixing-chambers, major and minor air-ducks arranged to aspirate liquid-fuel or its vapor from said reservoir to the respective mixing-chambers, and a throttle controlling the air-flow through the two ducts arranged to increase the relative proportion of air passing through the minor duct as the total flow is decreased.

10. In combination in a liquid-fuel and air mixer, an anterior air supply, a major mixing-chamber, a minor mixing-chamber, a fuel reservoir having its liquid level below both mixing-chambers, a major air duct and a minor air duct arranged to aspirate liquid fuel or its vapor from said reservoir to the mixing-chambers, valve means controlling the air flow through the two ducts, and means cooperating with said minor air duct to give a relatively greater aspirating effect for a given volume flow of air through said minor air duct than the aspirating effect for the same volume flow through the major air duct.

In testimony whereof I have hereunto set my hand in the presence of two subscribing witnesses, the 15th day of August 1906.

EDWARD P. NOYES.
